COMBINED AIR INTAKE AND VENTILATOR CAP

Steven L. Wahlstrom, West Covina, Calif., assignor to Pioneer Manufacturing Co., Los Angeles, Calif., a corporation of California

Filed Apr. 11, 1960, Ser. No. 60,150

Term of patent 7 years

(Cl. D62—3)

FIGURE 1 is a perspective view of a combined air intake and ventilator cap showing my new design;

FIG. 2 is a top plan view thereof on an enlarged scale;

FIG. 3 is an end view thereof on an enlarged scale as seen from the left of FIGS. 1 and 2;

FIG. 4 is a side elevational view thereof on an enlarged scale;

FIG. 5 is a sectional view thereof on an enlarged scale and taken along the line 5—5 on FIG. 2.

The bottom and side not shown are substantially like the top and side shown in FIGS. 2 and 4, respectively.

I claim:

The ornamental design for a combined air intake and ventilator cap, substantially as shown and described.
